AUTOMATIC CONTROL MECHANISM FOR
WINDMILL PUMPS

John B. Edgar, Lind, Wash.

Application September 24, 1937, Serial No. 165,592

1 Claim. (Cl. 103—23)

This invention relates to an automatic control mechanism for windmill pumps, particularly employed to pump a supply of water to a reservoir for farm use.

5 It is an object of the invention to provide means for automatically controlling the operation of the windmill pump so that the supply of water in the reservoir is maintained at a predetermined level and which is actuated by the 10 overflow of water from the reservoir.

A further object of the invention resides in providing a mechanism of the above-mentioned character which may be readily attached to the conventional windmill pump, is simple and durable in construction, efficient and reliable in operation and inexpensive to manufacture.

Other objects and advantages of the invention will be apparent during the course of the following description.

20 In the accompanying drawing, forming a part of this specification and in which like numerals are employed to designate like parts throughout the same,

Fig. 1 is a side elevation of a windmill showing the control mechanism applied thereto,

25 Fig. 2 is a detail sectional view of the mechanism for controlling the gearing of the windmill between the windwheel and pump,

Fig. 3 is a fragmentary sectional view of the 30 water container which is connected with the control mechanism of the gearing,

Fig. 4 is a detail sectional view of a modification of the invention, and

35 Fig. 5 is an elevation, partly in section, of another modification of the invention.

In the drawing, wherein for the purpose of illustration, I have shown a preferred embodiment of my invention, the numeral 5 denotes a conventional windmill tower, supporting on its top a windwheel 6 having its shaft 7 connected with the crank shaft 8 by means of gears 9 and 10, respectively mounted on the shafts 7 and 8. The crank of the crank shaft 8 is connected to the pump rod 11 and upon operation of the windwheel, the pump rod is reciprocated to deliver water from the pump 12 which is discharged through the pipe 13 into the water reservoir 14. The gear 10 is slidably mounted on the shaft 8 and is provided with a collar 15 engaged by the fork 16 of the actuating lever 17 pivotally mounted, as at 18, in the turn-table 19. A cross arm 20 is formed integral with the lower end of the lever 17, having a weight 21 suspended from one end and a fork 22 formed at its opposite end 55 which loosely engages in the annular groove 23

formed in the sleeve 24 slidably mounted on the pump rod 11. An arm 25 extends laterally from the sleeve 24 to which one end of a cable 26 is attached. The cable 26 extends downwardly in parallel relation to the pump rod and connected to the lower end of the cable is a hollow cylindrical container 27. In a dug well the container 27 is suspended within the well below the surface of the ground, as shown in Fig. 1, but if applied to a drilled well, a chamber 28 is formed 5 in the ground adjacent to the pump casing as shown in Fig. 4, with an opening 29 establishing communication between the chamber and pump casing and the container 27 is suspended within the chamber. In Fig. 5, another manner of 10 mounting the container 27 is disclosed, in which the container is constructed with a central passage 30 extending longitudinally of the container through which the pump casing extends, the container being free to slide longitudinally of the 15 pump casing. An overflow pipe 31 extends from the reservoir 14 having its discharge end slidably mounted through the top of the container 27 and terminating in spaced relation to the bottom thereof. The bottom of the container 27 is provided with a series of openings 32 of varying sizes 20 all of which with the exception of one are normally closed by removable plugs 33.

When the windmill is operating water is 25 pumped into the reservoir 14 which on becoming full overflows through the pipe 31 which discharges water into the container 27. The weight of the water in the container 27 causes the same to move downwardly pulling the cable 26 which pulls the sleeve 24 downwardly thereby rocking 30 the lever 17 which slides the gear 10 out-of-mesh with the gear 9 disconnecting the windwheel shaft from the crank shaft stopping the pump. The water in the container 27 slowly discharges 35 through the open opening 32 in the bottom of the container at all times and when the supply of water from the overflow pipe ceases, the water is drained from the container and the weight 21 rocks the lever 17 to shift the gear 10 into mesh with the gear 9, at the same time pulling the 40 cable 26 upwardly to return the container 27 to its normal position. If it is desired to accelerate the draining of the water from the container 27, the plugs 33 may be removed from the other 45 openings 32 in the bottom thereof. Thus, it is 50 seen the starting and stopping of the pump is controlled by the overflow of water from the reservoir 14 so the supply of water in the reservoir is maintained at a predetermined level.

It is to be understood that the form of my 55

invention herein shown and described is to be taken as a preferred example of the same and that certain changes in the shape, size and arrangement of the parts may be made without departing from the spirit of the invention or the scope of the subjoined claim.

Having thus described my invention, I claim:—

A control mechanism for windmill pumps including a windwheel and a pump having a rod operated thereby, a reservoir for holding the water discharged by the pump, transmission gearing between the windwheel and pump rod, a lever for shifting said gearing into and out-of mesh, a counterbalanced arm carried by said lever normally hold-

ing said gearing in mesh, a sleeve slidably mounted on the pump rod having connection with one end of said arm, a cable connected at one end with said sleeve, a hollow container suspended from the lower end of said cable, and an overflow pipe extending from said reservoir having its discharge end extending through the top of said container and terminating near the bottom thereof for discharging water into said container whereby the container is caused to move downwardly and pull said cable to actuate said counterbalance arm, said container having drain openings in the bottom thereof.

JOHN B. EDGAR.
